ROTARY BARKING MACHINE

Elry D. Crank, Buckner, Ark.

Application March 6, 1952, Serial No. 275,078

9 Claims. (Cl. 144—208)

This invention relates to a machine whereby cut and trimmed logs may be progressively barked as they are passed through the machine to prepare them for sawing into lumber in order that the waste or slabs cut therefrom may be used in the paper industry.

In the pulp and paper industry it is necessary that bark be removed from the waste slabs before the wood can be used for pulp. The sawmill industry normally produces enough waste slabs from logs in the process of sawing them into lumber to supply the paper industry with pulp wood if the bark could be economically removed. While there has been devised means for removing bark from logs by other methods, the other methods have been too expensive to be commercially feasible. It is therefore desirable to provide a machine which will quickly and economically remove bark from logs for use in the pulp and paper industry.

The primary object of this invention is to provide an improved machine for removing bark from logs, said machine being so designed as to accommodate logs of various sizes and having means for compensating for the crookedness and twisting of the logs whereby all of the bark may be removed from the log in a single operation.

Another object of this invention is to provide an improved debarking head through which logs may be passed and the bark removed therefrom due to the contact of brush means carried by said head with the log passing therethrough.

Another object of this invention is to provide an improved machine for barking logs, said machine including a wheeled carriage on which the debarking head is mounted whereby said barking machine may move transversely of the length of the log in order to automatically compensate for any crookedness in the log.

Another object of this invention is to provide an improved machine for removing bark from logs, said machine including a frame pivotally mounted on a carriage whereby a debarking head associated with the frame may be vertically adjusted automatically in order to compensate for the vertical variations in the logs being debarked.

Another object of this invention is to provide an improved machine for removing bark from logs, said machine having means for removing the bark whereby it may be quickly stripped of its bark in a single operation without the loss of any of the pulp wood of the log, said machine performing the debarking process at a cost which is economically feasible. A further object of this invention is to provide an improved debarking head which includes a sleeve rotatably mounted with respect to a frame, said sleeve having a plurality of log engaging brushes mounted therein for scraping said log and removing bark therefrom, said debarking brushes being formed of short lengths of steel cable.

With these objects definitely in view, this invention resides in certain novel features of construction, combination and arrangement of elements and portions as will

be hereinafter described in detail in the specification, particularly pointed out in the appended claims, and illustrated in the accompanying drawings which form a material part of this specification, and in which:

5 Figure 1 is a top plan view of the barking machine for removing bark from logs, said machine having associated therewith a trackway and a carriage for moving logs through said barking machine in order to remove bark therefrom, a log being shown prior to its entrance in the debarking head of the barking machine;

10 Figure 2 is a side elevational view of the barking machine of Figure 1 and showing the general construction of the barking machine including the wheeled carriage, a frame pivotally mounted on a wheeled carriage, a debarking head carried by said frame, and drive means mounted on said frame for driving said debarking means;

15 Figure 3 is an end elevational view of the barking machine of Figure 1 and showing a log prior to its entrance in the debarking head of the machine, the specific mounting for a front trackway for guiding and bracing the front of the frame being clearly shown;

20 Figure 4 is an enlarged transverse vertical sectional view through the debarking head of the barking machine and taken substantially upon the plane indicated by the Section line 4—4 of Figure 2, the specific relationship of the rotating sleeve and the log engaging brushes mounted therein being clearly illustrated;

25 Figure 5 is an enlarged fragmentary transverse vertical sectional view taken substantially upon the plane indicated by the section line 5—5 of Figure 3 and showing the manner in which the front support is pivotally mounted and spring urged with respect to the carriage;

30 Figure 6 is an enlarged fragmentary transverse vertical sectional view taken substantially upon the plane indicated by the section line 6—6 of Figure 1 and showing the manner in which the frame is pivotally mounted on a fulcrum carried by said wheeled carriage;

35 Figure 7 is an enlarged exploded perspective view of a log engaging debarking device and its associated holder; and,

40 Figure 8 is an enlarged fragmentary perspective view of the upper end of the front trackway and clearly shows the construction of a vertically adjustable socket slidably mounted within said front trackway, said socket being adapted for engagement with the front end of the frame pivotally mounted on the carriage.

45 Similar characters of reference designate similar or identical elements and portions throughout the different views of the drawings.

50 Referring now to the drawings in detail, it will be seen that there is illustrated in Figures 1 and 2 the specific barking machine, which is the subject of this invention. The barking machine includes a flat carriage

55 having a plurality of wheels 12 supporting same from a trackway 14. It will be understood that the carriage 10 is free to move along said trackway 14. Located near the center of the carriage 10 is a pair of triangular support members 16 extending upwardly therefrom and having one apex thereof at the upper end of each of

60 the triangular support members. Pivotally supported on the support members 16 forming the fulcrum, in a manner which will be explained in more detail, is a frame 18 which has mounted on the rear end thereof a power unit 20 which is illustrated as an internal combustion engine, but may be in the form of any type of conventional power unit including electric motors, etc.

65 Carried at the forward end of the frame 18 is a debarking head 22 which is driven by the power unit 20. Mounted on the rear of the carriage 10 and disposed beneath the rear end of the frame 18 is a hydraulic cylinder 24 for tilting the frame 18, the specific construction of the hydraulic cylinder 24 will be explained

in more detail hereinafter. The forward end of the frame 18 is guided and braced by a front trackway which is referred to in general by the reference numeral 26.

Referring now to Figures 2 and 6 in detail, it will be seen that the triangular support members 16 forming the fulcrum for the frame 18 have horizontally aligned openings 28 adjacent the upper end thereof in which are mounted bearings 30. Extending between and rotatably mounted within the bearings 30 is a pivot shaft 32 to which are secured a pair of L-shaped support members 34. One flange of each of the L-shaped support members is mounted on the pivot shaft 32 and the other flange thereof is secured to the underside of the frame 18. In view of the foregoing, it will be seen that the frame 18 is readily mounted for pivotal movement with respect to the support members 16 and the carriage 10 to which they are secured.

Referring now to Figures 1 and 2 in particular, it will be seen that the frame 18 includes a generally L-shaped frame member 36 which is generally rectangular in cross-section and forms the rear and center portion of the frame 18. The frame 36 has a centrally located projecting portion 38 on the front end thereof to which is secured the debarking head 22. The debarking head 22 includes a housing 40 having spaced L-shaped support members 42 secured to the rear outer surface thereof, one flange of each of the L-shaped support members 42 being disposed on each side of the projecting portion 38 and secured thereto by bolts 44. Extending from the front end of the housing 40 and secured to the front trackway in a special manner, which will be referred to in more detail hereinafter, is a front supporting arm 46.

Rotatably mounted within the housing 40 is a sleeve 43 which has mounted on one outer end thereof a drive sprocket 50. The power unit 20 is also provided with a drive sprocket 52, and a drive chain 54 is engaged over the sprockets 50 and 52 in order that the sleeve 43 may be rotated by the power unit 20.

Referring now to Figures 3, 5 and 8 in particular, it will be seen that the front trackway 26 includes a generally channel shaped column 56, the channel shaped column 56 having inturned wing flanges whereby it is substantially C-shaped. Slidably mounted within the upper portion of the column 56 is a connecting block 58 which has generally the same cross section as the interior of the C-shaped column 56 and is solid. The connecting block 58 has a curved recess 60 in the outer side wall thereof in alignment with the space between the wing flanges of the column 56. As is best illustrated in Figure 2, the front supporting arm 46 of the frame 18 has a curved forward end which is fitted within the curve recess 60 of the connecting block 58.

Referring now to Figure 3 in particular, it will be seen that the bottom end of the column 56 has mounted therein a second connecting block 62 which is rigidly secured to the column 56 and has a rounded lower end portion. The connecting block 62 is rotatably mounted on a pivot shaft 64 extending between and supported by a pair of spaced L-shaped mounting brackets 66 carried by the carriage 10. In order that the column 56 may be urged into engagement with the front supporting arm 46 the pivot shaft 64 has mounted thereon a spiral spring 68 which has its end portions 70 engaging the upper surface of the carriage 10 and which has the intermediate portion 72 engaging the connecting block 62 and urging the column 56 about the pivot shaft 64. In order that the column 56 may be suitably braced, the pivot shaft 64 has mounted thereon exteriorly of the mounting bracket 66 a pair of diagonal braces 74 which have their upper ends secured to the column 56 by conventional bolts 76. In order that the braces 74, the mounting brackets 66, the spring 68 and the connecting block 62 may be secured onto the pivot

shaft 64, the ends of the pivot shaft are enlarged as at 77.

Due to the novel connection between the front trackway 26 and the carriage 10 and the debarking head 22, the debarking head may be pivoted about the fulcrum formed by the supporting member 16 and remain continuously guided and braced by the front trackway 26. It will be understood that the front trackway 26 does not apply vertical pressure to the debarking head 22, but braces the head against forces acting axially of the head and tending to cause skewing of the frame or lateral movement of the head with respect to the carriage 10.

Referring now to Figure 4 in particular, it will be seen that the housing 40 is in the form of an annular ring which is U-shaped in cross-section and has mounted therein for rotation with respect thereto the sleeve 43. The housing 40 includes a web portion 78 and side flange portions 80 with circumferentially spaced bolts 82 extending between and secured to the side flanges 80. Mounted on each of the bolts 82 within the house 40 are a pair of outer spacer sleeves 84 and an inner spacer sleeve 86. Mounted on the bolt 82 between the outer spacer sleeves 84 and the inner spacer sleeve 86 is a pair of bearings 88 whose outer races are in spaced parallel relation and engage the outer surface of the sleeve 43. In order that the position of the sleeve 43 with respect to the housing 40 may be maintained, the sleeve is provided with a pair of spaced annular flanges 90 and 92 which engage the opposite outer surfaces of the flange portions 80 of the housing 40. In order that the logs passed through the sleeve 43 may be debarked, the sleeve 43 is provided with a plurality of mounting ears 94 between which are holders 96 pivotally mounted on chordal axes, said holders 96 having pivot pins 98 extending from opposite sides thereof and engaging in apertures in the mounting ears 94. Disposed within each holder 96 is a debarking brush 100 which is retained within its respective holder by a setscrew 102. It will be understood that the debarking brushes 100 are formed of short lengths of wire cables with ends intended to engage the bark of the logs passed through sleeve 43 and remove bark therefrom. In order that the holders 96 and their respective debarking brushes 100 may be retained generally at an angle normal to the log disposed within the sleeve 43, the holder 96 is provided with a pair of spaced mounting ears 104 to which are pivotally secured a pin 106. The opposite end of the pin 106 is disposed within a bracket 108 and a compressible coil spring 110 is mounted on the pin 106 and engages against the bracket 108 and the holder 96.

As is best illustrated in Figures 2 and 4, it will be seen that the brush holders 96 and the debarking brushes 100 are mounted in circumferentially extending sets of equal length brushes, the sets being spaced longitudinally of the sleeve 43, and the brushes of each set being circumferentially out of phase with respect to the brushes of the other sets so as to provide room for the brushes and their associated brush holders to pivot outwardly toward the sleeve 43. It will also be noted that, as between the different sets, the brushes 100 are of different lengths so as to provide for debarking logs of various diameters. When a small diameter log is passed through the sleeve 43, only the longer brushes of the numerous brushes mounted within the sleeve 43 engage the log and removes the bark from same. When a larger diameter log is passed through the sleeve 43, the longer brushes 100 are pivoted towards the sleeve 43 against the resistance of the coil springs 110 mounted on the pins 106 and are thus moved to a position out of engagement with the bark of the log. When the longer brushes 100 are in this position the shorter brushes 100 will remove the bark from the log.

Referring now to Figure 1 in particular, it will be seen that a log 112 is mounted on a carriage 114 which is provided with wheels 116 and rolls along a track 120. The carriage 114 is of a conventional type and need not be

described in detail other than the fact that it is utilized to convey the log 112 into the debarking head 22 and within the sleeve 48. The sleeve 48 is rotated by the drive unit 20 and the brushes 100 clean the bark from the log 112. It will be understood that the log 112 is pushed through the sleeve 48 by the carriage 114 and comes out the other end of the sleeve and is received by some conventional supporting means (not shown). Since the log 112 is not necessarily straight, but may be bent both upwardly and sideways, it is necessary that the debarking head 22 be free to shift in order to retain the sleeve 48 and the debarking brushes 100 in alignment with the contour of the log 112. As the log 112 is passed through the sleeve 48 the entire barking machine is free to move transversely of the axis of the trackway 120 by the movement of the entire assembly along the trackway 14 due to the mounting of the carriage 10 on the wheels 12. Also, the debarking head 22 is free to move upwardly and downwardly due to the pivotal mounting of the frame 18 on the supporting member 16.

Referring now to Figure 2 in particular, it will be seen that the cylinder 24 is rigidly connected to the carriage and pivotally connected by a shackle 142 to a mounting bracket 122 carried by the frame 18 adjacent the rear of the L-shaped frame portion 36. The cylinder 24 is a two way cylinder and has connected thereto hose lines 124 and 126. The hose lines 124 and 126 are connected to a pressure tank 130 carried by the L-shaped frame portion 36. Also mounted on L-shaped frame 36 is a compressor 132 which is connected to the pressure tank 130 by a line 128. The compressor 132 has a pulley 134 on one end thereof in alignment with a pulley 136 mounted on the forward end of the power unit 20. A belt 138 is entrained over, and connects, the pulleys 134 and 136. While it has not been illustrated, the cylinder 24 is provided with a conventional valve structure whereby the plunger 140 mounted therein may be either extended or retracted in order to tilt the frame 18 and thereby shift the debarking head 22 vertically. When it is desired to move a log 112 into the debarking head 22, the associated sleeve 48 is aligned with the end of the log 112 by shifting the carriage 10 along the trackway 14 and by utilizing the cylinder 24 to pivot the frame 18.

It will be understood that the pressure of the brushes 100 with respect to the log 112 is only such that the bark will be removed from the log 112 and that the pulp wood will not be damaged.

The operation of this device will be understood from the foregoing description of the details thereof, taken in connection with the above recited objects and drawings. Further description would appear to be unnecessary.

Minor modifications of the device, varying in minor details from the embodiment of the device illustrated and described herein, may be resorted to without departure from the scope of this invention, as defined in the appended claims.

Having described the invention, what is claimed as new is:

1. A log debarking head comprising a horizontally disposed sleeve mounted for rotation on a longitudinal axis, a plurality of debarking brushes pivotally mounted on the inner periphery of said sleeve on chordal axes transverse to the longitudinal axis of rotation thereof for engagement with a log being moved longitudinally into said debarking head, said debarking brushes each including a brush holder, a wire brush removably mounted in said brush holder, said brush holder being spring urged into a position normal to the longitudinal axis of the debarking head to which it is attached for tending to attain a position normal to the axis of a log to be debarked.

2. A log debarking head comprising a horizontally disposed sleeve mounted for rotation on a longitudinal axis, a plurality of debarking brushes pivotally mounted on the inner periphery of said sleeve on chordal axes transverse to the axis of rotation thereof for engagement with

a log being moved longitudinally into said debarking head, said debarking brushes being mounted in circumferentially extending sets of brushes, the sets being spaced axially of the sleeve, and the brushes of each set being located circumferentially out of phase relative to the brushes of the other sets.

3. A log debarking head as set forth in claim 2 wherein said brushes are stiff wire cables of varying lengths for debarking logs of varying diameters.

4. A debarking machine comprising a track mounted carriage, a fulcrum mounted on and near the center of said carriage, a frame overlying said carriage and pivotally mounted on said fulcrum for movement about an axis extending transversely of said frame and carriage, a debarking head carried at the forward end of said frame, a front guideway carried by said carriage and engaging said head to prevent skewing of said frame and to restrain said head against transverse movement with respect to said carriage, and means mounted on said frame rearwardly of said fulcrum for driving said debarking head.

5. A debarking machine comprising a track mounted carriage, a fulcrum mounted on and near the center of said carriage, a frame overlying said carriage and pivotally mounted on said fulcrum for movement about an axis extending transversely of said frame and carriage, a debarking head carried at the forward end of said frame, a front guideway carried by said carriage and engaging said head to prevent skewing of said frame and to restrain said head against transverse movement with respect to said carriage, means mounted on said frame rearwardly of said fulcrum for driving said debarking head, and means carried at the rear of said carriage and connected to said frame for tilting same.

35 6. A debarking machine comprising a track mounted carriage, a fulcrum mounted on and near the center of said carriage, a frame overlying said carriage and pivotally mounted on said fulcrum for movement about an axis extending transversely of said frame and carriage, a debarking head carried at the forward end of said frame, a front guideway carried by said carriage and engaging said head to prevent skewing of said frame and to restrain said head against transverse movement with respect to said carriage, means mounted on said frame rearwardly of said fulcrum for driving said debarking head, and means carried at the rear of said carriage and connected to said frame for tilting same, the last mentioned means being powered by the first mentioned means.

7. A debarking machine comprising a wheeled carriage movable forwardly or rearwardly, a fulcrum mounted on and near the center of said carriage, a frame overlying said carriage and pivotally mounted on said fulcrum for movement about a transverse axis, a debarking head mounted on a forward end of said frame for rotation about a transverse axis parallel to said fulcrum axis, a front trackway pivotally mounted on said carriage for movement about a transverse axis also parallel to said fulcrum axis, said trackway having slidable means engaging the front end of said frame for guiding said debarking head and frame for pivotal movement about said fulcrum axis, drive means for said debarking head mounted on said frame rearwardly of said fulcrum, and a resilient means operatively connected between said front trackway and said carriage for biasing said trackway towards said frame to maintain said slidable means in engagement with the front end of said frame.

8. A debarking machine comprising a track mounted carriage, a fulcrum mounted on and near the center of said carriage, a frame overlying said carriage and pivotally mounted on said fulcrum for movement about an axis extending transversely of said frame and carriage, a debarking head carried at the forward end of said frame, said debarking head including a housing rigid with said frame, and a sleeve rotatably mounted in said housing, a front guideway carried by said carriage and

engaging said head to prevent skewing of said frame and to restrain said head against transverse movement with respect to said carriage, and means mounted on said frame rearwardly of said fulcrum for rotating the sleeve of said debarking head.

9. A log debarking head comprising a horizontally disposed sleeve mounted for rotation on a longitudinal axis, a plurality of debarking brushes pivotally mounted on the inner periphery of said sleeve on chordal axes transverse to the longitudinal axis of rotation thereof for engagement with a log being moved longitudinally into said debarking head, said debarking brushes each including a brush holder, a wire brush removably mounted in said brush holder, said brush holder being spring urged into a position normal to the longitudinal axis of sleeve to which it is attached, said debarking brushes being mounted in circumferentially extending sets of equal length brushes, the sets being spaced axially, the brushes

10

15

of each set being located circumferentially out of phase with respect to the brushes of the other sets and tending to assume a position normal to an axis of the log to be debarked, and the equal length brushes of each set having a different length than the brushes of other sets.
